PLASTIC DISPENSING MAGAZINE FOR PADS OF TISSUE PAPER, COTTON AND THE LIKE

John Schwarz, Glendale, Calif.

Application July 2, 1956, Serial No. 42,122

Term of patent 14 years

(Cl. D4—3)

The single figure of the drawing is a perspective view of a plastic dispensing magazine for pads of tissue paper, cotton and the like embodying my new design.

The undisclosed side and rear of the plastic dispensing magazine are plain in appearance.

I claim:

The ornamental design for a plastic dispensing magazine for pads of tissue paper, cotton and the like, substantially as shown and described.
